UNITED STATES PATENT OFFICE

2,421,804

APPARATUS FOR REMOVING MELTABLE METAL FROM ARTICLES

George R. Park, Monaca, Pa.

Application October 31, 1944, Serial No. 561,302

6 Claims. (Cl. 266—38)

1

This invention relates to apparatus for removing meltable metal from articles and more particularly to the removal of Babbitt metal from such devices as babbitted bearings or the like to prepare them for re-babbitting.

A primary object of this invention is the provision of an improved device comprising a heated tank, adapted for improved removal of such worn Babbitt metal.

An additional object of this invention is the provision of such a tank, provided with pumping means in association therewith, whereby the recovered babbitt may be readily removed from the tank and reutilized in molten state.

As conducive to a clearer understanding of this invention it may here be pointed out that prior to the method and apparatus herein described customary method of removing worn babbitt from babbitt bearings or the like required the removal of the metal from the bearing shell with a torch. The cooled babbitt was then scraped off the floor or similar locality, and remelted, for reutilization. Such method required not only the remelting of the Babbitt metal but the retreatment of the shell, including re-tinning and re-heating the same before a new bearing could be poured. The instant invention contemplates the removal of worn Babbitt metal by the introduction of the bearing or the like into a bath of molten Babbitt metal, whereby the molten babbitt removes the old babbitt in its entirety without harmful effect on the tinned surface of the bearing shell. The old babbitt is then in a molten state, in the tank and ready for immediate reuse. Correspondingly, the bearing shell needs no further preparation being already heated and ready for re-pouring. Thus it will be seen that the instant apparatus obviates several hitherto important difficulties in the removal and re-babbitting of bearings or analogous devices.

Other objects will in part be obvious and in part pointed out as the description of the invention proceeds, and shown in the accompanying drawings wherein there is disclosed a preferred form of this inventive concept.

In the drawings:

Figure 1 is a top plan view of one form of tank constructed in accordance with this invention.

Figure 2 is a side elevational view of the device shown in Figure 1.

Figure 3 is a sectional view taken substantially along the line 3—3 of Figure 1, as viewed in the direction indicated by the arrows.

Figure 4 is a sectional view taken substantially along the line 4—4 of Figure 2 as viewed in the direction indicated by the arrows.

Figure 5 is an enlarged detail sectional view of one form of pumping apparatus utilized in conjunction with the instant invention.

Figure 6 is a sectional view taken substantially

2

on the line 6—6 of Figure 5 as viewed in the direction indicated by the arrows, and

Figure 7 is a sectional view similar to Figure 4 but disclosing a modified form of construction.

Like reference numerals refer to like parts throughout the several views of the drawings.

Having reference now to the drawings, there is shown at 10 a suitable metal tank having a semi-cylindrical bottom portion 11 adapted to be carried by suitable arcuate members 12 supported by heavy duty supports 13, beneath which arcuate bottom is positioned a suitable heating unit 14 of any desired type, as for example, a gas burner or electrical heating element. One extremity of the tank is provided with an inclined surface 15 of generally conical form terminating at its upper edge in an arcuate rim 16, and a partition 17 is positioned across the tank at its junction with the conical portion to form a working bay in which the pump mechanism is housed.

Pivotedly mounted as at 21 on an arm 20 extending upwardly from the partition 17 midway of its length, is a rock arm 22, to the extremities of which are pivotally secured as by pivots 23 legs 24 having their opposite extremities pivotally secured as by pivots 25 to levers 26. Levers 26 are, in turn, secured as by pivots 27 to the side walls of the tank 10 and terminate in operating handles 28.

As best shown in Figure 4, the rock arm 22 has pivotally secured thereto between the pivot 21 and its extremities, as by pivots 30, piston rods 31 the opposite extremities of which are secured as by pivots 32 to pumps generally indicated at 33 each comprising upper and lower telescoping cylinders 34 and 35, the arrangement being such that the cylinders 34 are adapted to reciprocate upwardly and downwardly on the cylinders 35 as the arm 22 is rocked about its pivot 21. The cylinders 34 of the pumps are provided with inlet ports 39 to which inverted L-shaped inlet tubes 36 are connected. Supported for vertical sliding movement on pins 38 suspended from the end wall of each cylinder 34 is an upper flap valve which when the cylinder 34 is moved downwardly closes the port 39. A lower flap valve 40 is mounted for vertical movement on pins 41 which extend through suitable apertures in the bottom wall 42 of the cylinder 35. This wall 42 is formed with a discharge port 43. The lower ends of the cylinders 35 are threaded into sockets formed on blocks 45 mounted on the base of the tank 10, and communicate through pipe 44 with a common outlet 46 comprising a T from which a pipe 47 leads upwardly and over the rim of the tank. A suitable needle valve generally indicated at 50 comprises an inverted U-shaped bracket 52 in which a pointed valve stem 53 having a handle 54 is threaded in such a manner as to open and close a vent or aperture in the pipe 47. This

valve 50 is positioned immediately adjacent the exterior of the tank.

Suitable apertures 55 are provided, as best shown in Figure 4, near the bottom of partition 17 to permit the passage of metal therethrough so that the level of the metal in the working bay will equal that in the tank.

From the foregoing the operation of the device should now be readily understandable. Babbitt metal is first introduced in the tank 10 on the 10 side of the partition 17 away from the pump members 33, and the heater 14 energized to melt the same. Suitable thermostatic controls, as for example any desired type of pyrometer may serve to energize and deenergize the heater as desired.

When the Babbitt metal in the tank 10 has reached the desired degree of heat the bearing or the like from which it is desired to remove the Babbitt metal is introduced into the tank 10, whereupon the metal thereon will melt and readily flow therefrom thus increasing the supply of molten metal. When it is then desired to remove the metal from the tank 10 for rebabbing other bearings or that from which the metal has just been melted, the pumps 33 are energized by actuating the handles 28, whereupon the fluid metal flows through the inlet tubes 36 into the pumps 33 and out through the pipes 44 and 47. A suitable siphon tube 75 may extend from pipe 47 to a point below the level of tank 10 to a mold or the like, in which case a siphon effect is produced and the operation of the pumps may be discontinued after the first few strokes. When the mold is full the flow of metal may be stopped by breaking the siphon suction by opening valve 50.

Obviously, the position of the apertures 55 permit only clean metal to pass through the pumps 33, as any dirt, grease or the like deposited in the tank during the melting operation will rise to the surface of the fluid on the side of the partition 17, opposite the working bay and may be readily removed by skimming. Heavier particles will fall to the bottom of the tank below the level of the openings 55 where they will remain undisturbed until the device is shut down for cleaning.

In the modification disclosed in Figure 7, a similar tank 10 provided with a partition 17 is employed. Upon the partition are mounted two supports 60, carrying in suitable bearings 61 a crank shaft 62, carrying at one end a drive pulley 63 adapted to be connected with any suitable source of power. Connected to the crank arms of the crank shaft 62 are the piston rods 64 of pumps 65, each comprised of upper and lower telescopic cylinders 66 and 67, respectively. Each cylinder 66 is provided with an inlet port 68 adjacent which a pivotally mounted flap valve 69 is secured. The bottom walls 70 of the lower cylinders are provided with outlet ports adjacent which pivotally mounted flap valves 71 are secured, the arrangement being such that the upper valves 69 are closed on the compression strokes of the pumps and opened on the intake stroke, and the lower valves 71 operated in the reverse manner, whereby fluid is forced through outlet pipes 72 to a main outlet pipe 73 positioned in a manner similar to the pipes 44, 46.

The mode of operation of this latter apparatus is substantially identical to that previously described.

Now from the foregoing it will be seen that there is herein provided an apparatus accomplishing all the objects of this invention and

others including many advantages of great practical utility and commercial importance.

As many embodiments may be made of this inventive concept, and as many modifications 5 may be made in the embodiments hereinbefore shown and described, it is to be understood that all matter herein is to be interpreted merely as illustrative and not in a limiting sense.

I claim:

1. Apparatus comprising a tank having a working bay separated from the main portion of the tank by a partition wall, said bay having a rim of a height equal to the height of the tank, said tank being adapted to contain molten metal into which articles having adhering meltable metal are adapted to be immersed, the partition wall having submerged openings through which molten metal from the tank enters the bay, pumps submerged in the molten metal in the working bay for expelling molten metal therefrom and a siphon tube connected to the pumps through which molten metal may be extracted from the bay.

2. Apparatus comprising a tank having a working bay separated from the main portion of the tank by a partition wall, said bay having a rim of a height equal to the height of the tank, said tank being adapted to contain molten metal into which articles having adhering meltable metal are adapted to be immersed, the partition wall having submerged openings through which molten metal from the tank enters the bay, pumps submerged in the molten metal in the working bay for expelling molten metal therefrom, a siphon tube connected to the pumps through which molten metal may be extracted from the bay and a valved vent in the siphon tube for breaking the siphoning effect thereof.

3. Apparatus comprising a tank having a working bay separated from the main portion of the tank by a partition wall, said bay having a rim of a height equal to the height of the tank, said tank being adapted to contain molten metal into which articles having adhering meltable metals are adapted to be immersed, the partition wall having submerged openings through which molten metal from the tank enters the bay, pumps submerged in the molten metal in the working bay, a discharge pipe connected to the discharge ports of the pumps for directing molten metal discharged from the pumps over the rim of said bay, and a siphon tube connected to the discharge pipe through which molten metal may be extracted from the bay.

4. Apparatus comprising a tank having a working bay separated from the main portion of the tank by a partition wall, said bay having a rim of a height equal to the height of the tank, said tank being adapted to contain molten metal into which a bearing box containing a worn or defective babbitt bearing is adapted to be immersed, the partition wall having submerged openings through which molten metal from the tank enters the bay, pumps submerged in the molten metal in the working bay, a discharge pipe connected to the discharge ports of the pumps for directing molten metal discharged from the pumps over the rim of said bay, a siphon tube connected to the discharge pipe through which molten metal may be extracted from the bay and a valved vent adjacent the junction of the discharge pipe and the siphon tube for breaking the siphoning effect of said siphon tube.

5. Apparatus comprising a tank having a working bay separated from the main portion of

the tank by a partition wall, said bay having a rim of a height equal to the height of the tank, said tank being adapted to contain molten metal into which articles having adhering meltable metal are adapted to be immersed, the partition wall having submerged openings through which molten metal from the tank enters the bay, reciprocating pumps submerged in the molten metal in the working bay, means operable through the molten metal in said bay for operating said pumps to expel molten metal from said bay, a discharge pipe connected to the discharge ports of said pumps for directing molten metal discharged from the pumps over the rim of said bay and a siphon tube connected to the discharge 15 end of said discharge pipe.

6. Apparatus comprising a tank having a working bay separated from the main portion of the tank by a partition wall, said bay having a rim of a height equal to the height of the tank, 20 said tank being adapted to contain molten metal into which articles having adhering meltable metal are adapted to be immersed, the partition wall having submerged openings through which molten metal from the tank enters the bay, reciprocating pumps submerged in the molten 25

metal in the working bay, means operable through the molten metal in said bay for operating said pumps to expel molten metal from said bay, a discharge pipe connected to the discharge ports of said pumps for directing molten metal discharged from the pumps over the rim of said bay, a siphon tube connected to the discharge end of said discharge pipe and a valved vent in the discharge pipe near its junction with the siphon tube.
